UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC-FURNACE-RESISTOR SUPPORTING MEANS.

Application filed February 23, 1922. Serial No. 538,542.

To all whom it may concern:

Be it known that I, THOMAS A. REID, a citizen of the United States, and a resident of Wilkinsburg, in the county of Allegheny and State of Pennsylvania, have invented a new and useful Improvement in Electric-Furnace-Resistor Supporting Means, of which the following is a specification.

My invention relates to electric furnaces and particularly to electric resistance furnaces and it has for one of its objects to provide a relatively simple and easily assembled and disassembled heating element for an electric resistance furnace.

Another of its objects is to so form a metallic resistor member that it may be removably supported by only its ends.

Another of its objects is to provide a refractory support for a relatively heavy pre-formed resistor member that shall permit of quickly removing the resistor therefrom.

In practising my invention, I provide a furnace chamber in which is located a relatively heavy resistor member preformed to comprise a plurality of substantially parallel-extending, end-connected convolutions, which end connections are bent at substantially a right angle to the plane of the convolutions. I provide a plurality of spaced-apart sets of relatively narrow refractory supporting members of substantially T-shape, each member having a plurality of grooves in the inner surfaces of the inner end for operatively engaging the bent-over ends of the resistor member. The furnace is so constructed as to permit of inserting and removing the refractory supporting members laterally of the furnace chamber.

In the single sheet of drawings, Figure 1 is a view, in vertical lateral cross-section, of an electric resistance furnace comprising a device embodying my invention;

Fig. 2 is a partial longitudinal section thereof taken on the line II—II of Fig. 1;

Fig. 3 is a top plan view of a preformed resistor member;

Fig. 4 is an end view of the resistor member illustrated in Fig. 3, and

Fig. 5 is a view, in perspective, of one of the refractory resistor supporting members.

An electric resistance furnace comprises an outer metallic framework or skeleton 11 provided with suitable supporting members 12. A refractory lining comprises a floor

13, side walls 14 and a roof 15. The lining may comprise a plurality of bricks or blocks of any suitable refractory heat-insulating and high-temperature resisting material usually employed in the construction of such furnaces. While I have shown only a single lining for the floor and the side walls, it is to be understood that two linings may be employed if desired. The roof and the side walls are suitably spaced apart so as to form a furnace chamber 16 of any suitable or desired contour and dimensions.

The roof 15 is provided with an inner lining 17 comprising a plurality of bricks or blocks of a suitable high-temperature resisting refractory material, the bricks or blocks being built up in spaced-apart sections to provide a plurality of chambers 18 therebetween. The bricks or blocks adjacent the chambers 18 are provided with overhanging shoulder portions 19 so that the chamber 18 is of substantially T-shape. A plurality of relatively narrow refractory resistor-supporting members 20, of substantially T-shape, have their outer ends located in the chambers 18, being supported by the shoulder portions 19. The inner end of the members 20 is provided with a plurality of longitudinally extending grooves 21 located in the inner surface of the end portion thereof.

A block 22 of a suitable refractory material and of substantially L-shape is located at one end of each of the chambers 18 and substantially as thick as the width of the chamber. Two suitably shaped refractory blocks 23 and 24 are located within the block 22 and are quickly removable therefrom into the chamber 16, the block 23 being, of course, removed first. The members 20 may then be inserted into and removed from their proper position within the inner lining 17 through the space made vacant by the removal of the blocks 23 and 24.

A resistor member 25 comprises a plurality of end-connected and substantially parallel-extending convolutions formed of a relatively heavy and unyielding metallic rod or bar, the end connections being bent at substantially a right angle to the plane of the convolutions to be located in the grooves 21 of the members 20 and to thereby support the resistor member in its proper operative position in the furnace chamber adjacent the roof thereof. The number of convolu-

- tions may be made sufficiently large to permit of a single integral resistor member extending entirely across the width of the furnace chamber so that it is necessary to bring out only two end portions 26 through suitable openings in the furnace structure. If desired, a plurality of resistor members 25 may be located longitudinally of the furnace chamber and, if desired, the individual 10 resistor members may be connected in series-circuit relation, thus requiring that only two end portions 26 be brought out for the entire heating element of the furnace.
- If it is assumed that the resistor member 15 has been preformed to the proper dimensions and spacing between the parallel-extending convolutions and with the bent-down end connections, the method of assembly is substantially as follows:
- 20 The resistor member is held in substantially its proper operative position in the furnace chamber immediately below the lining 17 and the refractory supporting members 20 are inserted in the opening provided by the removed refractory members 23 and 24 laterally of the furnace until a sufficient number have been inserted with their outer ends in each of the chambers 18 to completely fill these chambers and with 25 the grooves 21 engaging the bent-down ends of the resistor to support the same. While I have illustrated six such refractory members as extending across the width of the furnace chamber, a large number may be 30 employed, and it is not essential that the members 20 are located in abutting relation, but they may be spaced apart relatively small distances, in accordance with the distance between the respective end connections at each end of the resistor members. It is, of course, apparent that the lateral width of the blocks 23 and 24 must be 35 slightly greater than the length of the members 20 to permit of their being easily and quickly inserted in and removed from their proper operative position in the furnace structure.
- The device embodying my invention thus 40 provides a relatively simple and easily assembled and disassembled heating element where a relatively heavy and preformed resistor member is employed, in which only the ends of the resistor members are in operative engagement with a refractory resistor support, the resistor member being, of 45 course, substantially self-supporting therebetween. By bending down the end connections of the convolutions and causing them to fit into relatively deep grooves, the middle portions of the convolutions of the resistor member are prevented from sagging any relatively large distance by the substantial interlocking of the bent-down end connections with the projecting shoulder portions of the inner end of the refractory sup-

porting member immediately outside of and adjacent the grooves.

Various modifications may be made in the device embodying my invention without departing from the spirit and scope thereof 70 and I desire that only such limitations shall be placed thereon as are imposed by the prior art or are specifically set forth in the appended claims.

I claim as my invention:

- 75 1. In an electric resistance furnace, in combination, a relatively heavy resistor preformed to comprise a plurality of integral substantially parallel-extending, end-connected convolutions and grooved means for supporting said resistors by portions thereof immediately adjacent to and including the end-connections at both ends thereof, the resistor being otherwise self-supporting.
- 80 2. In an electric resistance furnace, in combination, a plurality of walls enclosing a furnace chamber, a plurality of spaced-apart sets of refractory supporting members supported by said walls and having inner portions projecting into said chamber, and a relatively heavy preformed resistor member comprising a plurality of integral, substantially parallel-extending end-connected convolutions extending between said sets of supports and equally supported thereby immediately adjacent to both ends of said convolutions.
- 85 3. In an electric resistance furnace, in combination, a plurality of walls enclosing a furnace chamber, a plurality of spaced-apart sets of refractory members, of substantially T-shape, supported by said walls and having portions extending into said furnace chamber, and a relatively heavy preformed resistor member comprising a plurality of substantially parallel-extending end-connected convolutions, the end portions of said convolutions, only, operatively engaging said portions of T-shape to support said resistor members in said furnace chamber.
- 90 4. In an electric resistance furnace, in combination, a plurality of walls enclosing a furnace chamber, a plurality of spaced-apart sets of refractory members supported by said walls and having a portion extending into the furnace chamber provided with lateral extensions having spaced-apart grooves on the inner faces thereof, and a relatively heavy preformed resistor member comprising a plurality of substantially parallel-extending end-connected convolutions, the end connections being bent at substantially a right angle to the plane of said convolutions to be located in said grooves to support the resistor.
- 95 5. In an electric-resistance furnace, in combination, a plurality of grooved refractory members, and a relatively heavy resistor having return-bent end portions bent as an angle to the plane of the main portions
- 100 110 115 120 125 130

thereof, both end portions being located in said grooved refractory members.

6. In an electric-resistance furnace, in combination, a plurality of spaced and parallel-extending refractory members having a groove therein, and a relatively heavy resistor having return-bent end portions bent at right angles to the plane of the main portions of said resistor and fitting in said grooves.

7. In an electric-resistance furnace, in combination, a plurality of spaced sets of

elongated refractory members, of substantially T-shape in lateral section, and a relatively heavy preformed resistor member having return-bent end portions bent at substantially a right angle to the plane of the resistor and interfitting with the members of T-shape to support the weight substantially equally from each set.

In testimony whereof, I have hereunto subscribed my name this 20th day of February, 1922.

THOMAS A. REID.
